UNITED STATES PATENT OFFICE.

JOSEF SCHREIBER, OF VIENNA, AUSTRIA-HUNGARY.

FLASHER.

SPECIFICATION forming part of Letters Patent No. 337,524, dated March 9, 1886.

Application filed December 16, 1885. Serial No. 185,899. (No model.)

To all whom it may concern:

Be it known that I, JOSEF SCHREIBER, of the city of Vienna, in the Empire of Austria-Hungary, have invented certain new and useful 5 Improvements in Feeding Boilers with a Combination of Water in the Form of Fine Spray and Compressed Air, and of which I declare the following to be a specification.

My invention relates to improvements in feeding boilers with water-spray and compressed air, the boiler being fed with compressed air and water in finely-divided form in such manner that the water is converted into spray by the compressed air in being forced into the boiler, where the water spray is immediately converted into steam. The motive power consists, consequently, of a mixture of steam and air. The apparatus in which this mixture of air and steam is produced consists, principally, of a water-reservoir for feeding the boiler with water and an exterior mantle or casing arranged in suitable position above the water-reservoir. This said mantle or casing is provided with a suitable furnace, and contains the steam-boiler, which latter is subdivided into the steam-generating space and the superheating space or compartment. These two spaces or compartments are separated from each other by a suitable horizontal partition provided with appropriate valves for opening up the communication between the two said spaces or compartments. The superheater is provided with safety-valve, manometer, and steam-delivery pipe, while 35 the mantle or casing is provided with an outlet for the products of combustion, which circulate around the boiler and within the exterior mantle or casing, communicate their heat to the boiler and superheater surface, and finally escape through the aforesaid outlet to the chimney. A small steam-engine of suitable construction is mounted on a suitable bracket fixed to the mantle or casing, and sets a shaft in rotation by means of an appropriate crank, which said shaft has its bearings in two standards fixed to the base-plate above the water-receptacle. The shaft carries the fly-wheel, strap-drum, and two eccentrics, one of which drives an air-pump, 50 the other a water-pump. The said water-pump is arranged in the water-reservoir, and

is in communication with the boiler by means of a pipe or tube, whereas the air-pump is mounted on the cover to the water-reservoir, and also has a tube or pipe communicating 55 with the boiler, which said pipe is led into or connected to the water pipe of the water-pump, and is thus brought into communication with the generating space of the boiler.

In order to be able to vary the quantity of air and water fed to the boiler, the eccentrics can be so constructed that the same can be readily adjusted.

Figure 1 is a vertical section of my improved apparatus on the line *x y* in Fig. 3, 65 with the water-pump in section. Fig. 2 is a vertical section of the same figure on the line *x' y'*. Fig. 3 is a plan or top view of my improved apparatus. Fig. 4 is an elevation of the adjustable eccentric. Fig. 5 is an elevation of the sleeve or muff; and Fig. 6 an elevation of the eccentric.

The base-plate *D'* is mounted on the water-reservoir *D*, and carries the mantle or casing *A*. The mantle or casing *A* is lined with refractory material, and is provided with the furnace-grate *B*, and also a suitable outlet, *C*, for the spent products of combustion to the chimney. A number of brackets, *B'*, are arranged above the fire-proof or refractory lining, and serve to carry the steam-generator *A²*, which is separated from the superheater *A'* by a horizontal partition, *E'*, provided with suitable valves, *b*. The said superheater carries the safety-valve *F'* and the manometer *G'*, 75 which are so arranged that they stand above the cover of the exterior mantle or casing, *A*. A small steam-engine, *M*, the connecting-rod *M'* of which is connected to the crank *L'* of the crank-shaft *G*, is mounted on a bracket, *K'*, 80 fixed to the mantle or casing *A*. The said crank-shaft *G* has its bearings in the standards *N' O'*, carries the fly-wheel *P'*, the fixed and loose strap-drums *Q' Q''*, two eccentrics, *H H'*, and the eccentric *I'* of the regulating-slide of 85 the steam-engine. The eccentric *H* actuates the piston of the water-pump *F*, arranged in the water-reservoir in such manner that the suction-tube *E* will reach into the water in the said reservoir. The pump is provided with 90 valves in known manner, is extended beyond or above the base-plate *D'*, and carries laterally, 95 100

near its upper end, a pipe or tube, *f*, which communicates with the short tube *f'*. The eccentric *H* serves to actuate the pump *I*, mounted on the cover to the water-reservoir *D*, and carrying a pipe or tube, *g*, which is connected to the short pipe or tube *f'*. This said short pipe or tube *f'* is securely fixed to the mantle or casing *A*, and leads into a pipe or tube, *r*, arranged in the steam-generator.

10 The water and air pumps can be single or double acting.

The adjustable eccentric is constructed as follows: The sleeve or muff *l m n o* is keyed to the shaft *G*, the extension of which, *p q r s*, is of square form. An oblong opening, *t u v w*, is formed in the eccentric *H* in such manner that the shorter sides, *t u* and *v w*, are of like size with the square extension to the sleeve or muff *l m n o*, which fits exactly into the opening of the said eccentric, and can reciprocate in the same. The eccentric is fixed to the sleeve or muff by means of the disk or collar *P* and screws or bolts *a a*, whereas the position of the same can be regulated by means of the screws *S T U*, which are guided in small bearings in the eccentric *H*, so that they can operate on the said sleeve or muff. The eccentric is provided with appropriate graduations, *R*, which denote the atmospheric pressure under 20 which it is desired to work, and which correspond with the position of the eccentric.

The operation of the motor with the simultaneously-operating air and water pumps is as follows: By each revolution of the shaft *G* 35 a quantity of air and water corresponding to the diameter and stroke of the pistons of the pumps is forced through the two tubes or pipes *f g*, which are connected to the short tube or pipe *f'*, and through the pipe *r* into 40 the steam-generator *A'* in such manner that the water is converted into fine spray by the compressed air simultaneously injected. This water spray is rapidly converted into steam, the action of which is augmented by the expansion of the compressed air injected with 45 the feed-water. This admixture of steam and air passes through the valves *b* into the super-heater *A'*, and from thence through the tube or pipe *l* to the machine *M*, for driving the 50 same.

In gas-motors the greatest effect is obtained by a mixture of gas and air, and a like excellent effect can be obtained in steam-engines by employing a mixture of steam and air. If, by 55 means of suitable experiments, the most favorable proportions of air and water have been ascertained and the diameter of the pistons of the air and water pumps determined, the eccentrics are fixed so that at each stroke of the 60 pistons one and the same quantity of air and water will be continuously pumped into the steam-generator. If it is desired to increase the pressure in ordinary steam-boilers, it is only necessary to use a stronger fire, as the water to 65 be converted into steam is contained in the boiler; but as in the steam-generator described above no more water can be converted into

steam or air be expanded than is forced into the generator at each stroke of the pumps, and this quantity of water and air by continuous working cannot produce more steam-air than is injected by the next stroke, a stronger firing alone will not suffice to produce a greater pressure in the boiler or generator, but can only have effect when a large quantity of water and air is injected into the said steam-generator. If the pressure is to be reduced, the quantity of water and air fed to the generator must be decreased; but both of these operations can only be carried into effect by making 70 the stroke of the pumps adjustable. As, however, for small generators two and for larger generators four pumps—two water and two air pumps—are mounted on the same shaft, the customary mode of regulating the stroke—by 75 means of an adjustable disk at the end of the shaft—cannot be employed, and the adjustable eccentric therefore becomes an absolutely necessary requisite for this kind of feed.

The position which the eccentric must occupy in order to attain a maximum pressure in the generator, which said pressure cannot be exceeded by the most excessive firing, can be ascertained by a few experiments, the results of which are marked in atmospheres on 80 the graduated scale *R*. If, for instance, the engine is to be driven with a pressure not exceeding four atmospheres, the eccentric is adjusted to No. 4 of the graduations, and if the firing is not too weak a pressure will be attained 85 which will constantly remain at a little under four atmospheres. For small motors, where a variable pressure during the working is desirable, ordinary fixed eccentrics can be employed. The cylinders of the pumps are of 90 medium size, and the suction-pipe of the water-pump rendered adjustable by means of a screw, so that the inlet can be diminished or increased in area, and the pump force up more or less water, so that the pressure in the generator can be increased as may be desirable. The regulating-screw is provided with a pointer, *Z*, which moves over a suitably-graduated 95 scale corresponding, by previously-made experiments, with the desired number of atmospheres. As hereby the quantity of air and 100 water remains constant, the desired proportions of the mixture of steam and air will not always be the most effective, but, however, sufficient for small motors.

110 It will be evident from the foregoing specification that my improved method of feeding boilers with an admixture of compressed air and water in spray form can be applied to 115 boilers of almost any construction, form, or size, whether horizontal or vertical, and that the water-reservoir, and also the water and air pumps, can be placed in any desired position, either above, below, or laterally to the said boiler.

120 Although I have for clearness sake shown the application of my said invention to small motors, I desire it to be understood that I by no means confine myself to the special appli- 130

cation to such said small motors, as my said invention can be applied with like advantage to boilers of all sizes and systems.

Having now particularly described and ascertained the nature of my invention, what I claim is—

1. The combination of the adjustable eccentrics for regulating the stroke of the piston or connecting-rods by means of the four-cornered 10 or square part $p\ q\ r\ s$ of the muff or sleeve $l\ m\ n\ o$ with the oblong opening $t\ u\ v\ w$ in the eccentrics H or H' , which said four-cornered or square part $p\ q\ r\ s$ of the muff or sleeve $l\ m\ n\ o$ can be adjusted in the oblong opening $t\ u\ v\ w$ 15 in the eccentrics H or H' by means of the screws or screw-bolts $S\ T\ U$, substantially as described in the foregoing specification and shown in the accompanying drawings.
2. The combination of the sleeve or muff $l\ m\ n\ o$ and the square extension $p\ q\ r\ s$ to the same with the collar or disk P , the crank-shaft G , and the eccentric H or H' , substantially as 20

described in the foregoing specification and shown in the accompanying drawings.

3. In a feeding device for steam boilers or 25 generators, the combination of the water-pump F and water-reservoir D with the air-pump I and the adjustable eccentrics H and H' , substantially as and for the purpose set forth in the foregoing specification and shown in the accompanying drawings. 30

4. The combination of the eccentrics H and H' , and the water and air pumps $F\ I$, and the graduations R , substantially as and for the purpose set forth in the foregoing specification and 35 shown in the accompanying drawings.

In witness whereof I have hereunto signed my name in the presence of two subscribing witnesses.

JOSEF SCHREIBER.
